United States Patent Office.

CHARLES STARBUCK, OF PHILADELPHIA, PENNSYLVANIA.

Letters Patent No. 63,762, dated April 9, 1867.

IMPROVED CAM HITCHING HOOK.

The Schedule referred to in these Letters Patent and making part of the same.

TO ALL WHOM IT MAY CONCERN:

Be it known that I, CHARLES STARBUCK, of the city of Philadelphia, in the State of Pennsylvania, have invented a new and useful improvement in the hitching hook, which I term a "Cam Hook;" and I do hereby declare that the following is a full, clear, and exact description of the construction and operation of the same, reference being had to the accompanying drawings, making a part of this specification, in which—

Figure 1 is a side view of the improved hook as connecting the ends of two straps on a strain in opposite directions.

Figure 2, a like view of the said hook as opened for the detachment of one of the straps; and

Figure 3, a plan view of one of the sides of the closed hook at a right angle to the side shown in fig. 1—

Like letters of reference indicating the same parts when in the different figures.

The object of my invention is to afford a hook for hitching horses, and for other purposes requiring facility in attaching and detaching straps, ropes, chains, &c., that will be strong, effective, and more reliable and durable as a safe hitching hook without the employment of a spring in the same. It consists, substantially as hereinafter described, in the construction and application of a cam-lever provided at one end with a loop or eye to correspond with a like loop or eye on the shank end of the hook, and having its fulcrum in the said shank, so that the greater the strain or pull on the strap, rope, or chain passing through both of the said loops, the more securely will the opening in the hook be kept closed, and so that, while it will not be liable to fall open when the strain or pull has ceased, yet it can, when necessary, be opened with the most perfect facility and ease:

In the drawings, A is the main or shanked portion of the said hook, with a loop a'' , at its inner end; and A' the cam-lever, with a corresponding loop, a''' . B is a common ring, secured to the end of one of the straps C; and B' a large loop on the end of the opposite strap C', which has both of the loops a'' a''' of the levers A and A' strung loosely in connection with it. The main or shank portion of the lever A of the said hitching hook has a longitudinal slot made through the middle of its shank, which opens into the loop a''' of the same, and in this slot the cam-lever A' is secured so that it will vibrate easily upon a fulcrum-pin, and thus allow the loops of the said hook to be closed together, as in figs. 1 and 3, or separated from each other, as in fig. 2. The shorter end of the lever A' is formed so that it will fit along in the slot in lever A when the hook is closed, as in figs. 1 and 3, and at the same time present a curved and pointed stop, a^4 , which firmly closes the open end of the hook when the straps C and C' are drawn apart, and acts as a cam in preventing the escape of the ring B from the hook when the straps C and C' are slackened.

It will be readily seen that a pull made on either of the straps C or C' will force the two loops a'' and a''' of the hook together, and consequently close the open end of the hook, and also keep it closed by a power proportionate to that expended in pulling on the straps; and that when the strain on the said straps is relaxed or withdrawn the simple gravitation of the whole hook together will tend to prevent the escape of the ring B; and that, independently of this gravitation, the cam or curved form of the inner end of the lever A' will prevent the escape of the ring B, because, as the ring tends to press the curved end of the lever outward, it causes it to close upon the ring, and thus prevent its escape. It will also be seen that by slipping the loops a'' a''' of the hook around to the longer side of the loop of the strap C', and simply separating them, the hook will thereby be opened, as shown in fig. 2, so that the ring B can be dropped out or detached from the hook.

This is a very strong and reliable hitching hook, whether used for hitching horses or for other purposes, and being without any spring attachment, and also exceedingly simple of construction, it is not liable to get out of order by use.

I wish it to be understood that I do not intend to confine myself in the manufacture of this hook to the precise shape or form shown, nor to the use of the straps C C', or the ring B, because it is obvious that these attachments must be varied in material and strength, as well as form, to suit the various purposes for which the hook may be required. But having fully described my improvement in the hitching hook, what I claim as new therein of my invention, and desire to secure by Letters Patent, is confined to the following, viz:

I claim the construction and application of the cam-lever A', so that it will operate in combination with the main portion A of the hook, substantially in the manner described for the purposes specified.

CHARLES STARBUCK.
